CIRCULAR KNITTING MACHINE

Albert E. Page, Brooklyn, N. Y., assignor to Scott & Williams, Incorporated, New York, N. Y., a corporation of Massachusetts

Application August 6, 1936, Serial No. 94,655

16 Claims. (Cl. 66—42)

This invention relates to revolving needle cylinder, independent needle circular knitting machines, and more particularly to machines adapted to knit hosiery with a plurality of feeds in the leg and foot—and if desired, also in the welt.

In knitting stockings it is desirable to have a multiplicity of feeds in order to increase production. The modern circular knitting machine for making hosiery is a complex mechanism and it is very difficult to find room around its relatively small cylinder for the parts necessary to knit fabric at a multiple of feeds and to obtain the necessary timed, cooperative action of all the parts. One of the features of the present machine is its ability to knit a stepped high splice at each feed while knitting on a multiple of feeds, and another feature is the mechanism and manipulation necessary to introduce and remove the various yarns at the auxiliary feeds in proper timed relation.

The invention will be shown and described in the well-known Scott & Williams revolving needle cylinder machine for making an automatic in-turned welt such as shown and described in the patent to Robert W. Scott, No. 1,282,958, dated October 29, 1918.

In the drawings,

Fig. 1 is a plan view in section taken on the line 1—1 of Fig. 3 above the upper bedplate of a Scott & Williams revolving needle cylinder circular knitting machine embodying my invention, showing the knitting cams for the two auxiliary feeds and their controls while all feeds are in operation;

Fig. 2 is a side elevation of the lower part of a stocking with stepped high splice and sole reinforcement made on the new machine;

Fig. 3 is an elevation from the left side of the machine showing those thrust rods and connections which control the selecting and knitting cams and the yarn finger for the left auxiliary feed, on that side of the machine, the finger being shown in its operative position;

Fig. 4 is a plan view in horizontal section taken on the line 4—4 of Fig. 3 below the upper bedplate, showing the mechanism for selecting the pattern jacks;

Fig. 5 is a diagram showing the arrangement of the needles in the needle cylinder according to the lengths of their butts, the arrow showing the direction of their rotation;

Fig. 6 is a development of so much of the main pattern drum as contains the principal cams relating to the two auxiliary yarn feeds, the drum

cams and thrust rods being shown occupying their positions during making of a high splice;

Fig. 7 is a development from the inside of the upper cam ring, showing the paths of the pattern jacks, intermediate jacks and needles when splicing, and the arrows indicating the direction of their movement, the dotted lines indicating the variations from that path taken by the butts of the needles which do not splice while other needles are splicing, and the dot and dash and dotted lines indicating the variations from that path taken when no needles are splicing;

Fig. 8 is a plan view taken above the latch ring and dial-driving mechanism, the view showing the mechanism controlling the auxiliary yarn fingers;

Fig. 9 is a view of the yarn finger at the left auxiliary feed of the machine, showing its relation to the needles;

Fig. 10 is a view in elevation of the plate which guides the left auxiliary yarn finger to and from its operative position;

Fig. 11 is a view in elevation from the right side of the machine showing the mechanism for controlling the right auxiliary feed yarn finger and sinker cam and certain knitting cam controls;

Figs. 12 and 13 are detail views in elevation of the mechanism controlling the right auxiliary yarn finger, taken on the line 12—12 of Fig. 8; Fig. 12 showing the parts when the finger is feeding its body yarn but not its splicing yarn; and Fig. 13 showing the positions of the parts when the finger is entirely withdrawn;

Fig. 14 is a plan view of the dial and throat plate of the machine showing the various clamps, cutters and guards involved in the control of the yarns at the two auxiliary feeds;

Fig. 15 is a view in vertical section through the dial plate of Fig. 14 on the line 15—15, showing the main yarn cutter and clamp;

Fig. 16 is a view of the dial in side elevation, showing the auxiliary cutter and clamp and the guard for keeping the yarns from the first auxiliary feed out of the main yarn cutter;

Fig. 17 is a view in partial vertical section through a portion of the latch ring, taken on the line 17—17 of Fig. 8, showing the mechanism for controlling the two yarn cutters and clamps;

Fig. 18 is a plan view taken just above the latch ring on the line 18—18 of Fig. 11, showing the levers for controlling the auxiliary sinker cams and the flying latch protector;

Fig. 19 is a view in elevation of the camming

means controlling the clearing cam for the right auxiliary feed;

Fig. 20 is a development of the lower and upper cam rings in a modified form of the invention, showing the paths of the butts of the pattern jacks, intermediate jacks and needles, in a manner similar to that of Fig. 7; while

Fig. 21 is a side view of the pattern jack used in the modified machine of Fig. 20.

It has been known that it was desirable to reduce the length of time consumed by a circular knitting machine in making a stocking, and multiple feeds have been tried. Heretofore these attempts have not been satisfactory, partly because the amount of space around the circumference of the needle cylinder in which to place the various cams and other mechanisms operating on the needles, was too small to enable placement of all the necessary parts for a modern machine. The lack of success of these efforts was also partly due to the necessity for timing the auxiliary feed movements in such manner as not to upset the appearance of the stocking. In accordance with the present invention a machine has been devised in which the leg and foot—and if desired, also the welt—can be knit at three feeds, while the balance of the stocking is knit at one feed. At the same time the machine is able to produce splicing of varied widths for the high splice and the sole reinforcements at each feed. This is accomplished in the limited space available by making a variable selection, using it at a multiplicity of feeds, and thereafter destroying the selection and making a new one. In the example of the invention shown and described, each selection is kept for one revolution of the machine and then destroyed, and it is immediately followed by another selection. By devising mechanism using this selection for a multiplicity of times before destroying it, it is possible to use only one cycle of operations of the pattern jack mechanism for each three courses of the fabric, thereby cutting in one-third the space around the needle cylinder which has to be allowed for pattern jack selecting operations. The pattern jack and its selecting mechanism is described in greater detail in the patent to Ivan W. Grothey No. 1,678,385, dated July 24, 1928, and the patent to Albert E. Page No. 1,969,853, dated August 14, 1934.

General construction of the machine

The machine is of the well-known revolving needle cylinder type made by Scott & Williams, whose basic features are shown, for instance, in the patent to Robert W. Scott No. 1,152,850, dated September 18, 1915. The machine has lower and upper bedplates B and C, such as shown in the Page patent above mentioned, with a pattern jack 736 and intermediate jack 732 under each needle and a trick wheel 800 to select the jacks for the stepped splicing. The machine is also adapted to make an automatic inturned welt in accordance with the Robert W. Scott Patent No. 1,282,958, above mentioned. For this purpose it has a dial containing transfer bits (not shown), the dial being driven in synchronism with the needle cylinder by means of the vertical dial driving shaft 13. This shaft drives the usual dial spindle *a* through the intermediary of a bevel gear, meshing with a bevel pinion on a horizontal drive shaft 14. This in turn is connected to the vertical shaft 13 by means of bevel pinions. The shaft 13 is driven from the main bevel gear of the machine in the

usual manner. The short horizontal shaft 14 and the gears and pinions are protected by a cover 14'. This cover also acts as a supporting bracket, being mounted on the usual latch ring 550. The latch ring 550 is pivoted on the usual latch ring post 401 at the rear of the machine and is supported at the front of the machine by the widening picker post 400. On the upper end of the needle cylinder 260 is the usual sinker cap 300. In the throat plate 559 are located the 10 yarn fingers F and F' for the yarns to be fed to the needles at the regular knitting point.

Yarn feeding at the auxiliary feed points

In the machine shown in the drawings the 15 stocking is knit at the throat plate exclusively except during the leg and foot. The leg and foot are knit at three feeds, that is to say, three courses of stitches to each revolution of the machine. In addition to the knitting at the throat plate there is a first or left auxiliary feed at the 20 left side of the machine as the operator faces it, and a second or right auxiliary feed at the right of the machine as it appears in Figs. 1 and 8, and to the operator. The exact locations of 25 the left and right auxiliary feeds are indicated at 185 and 186 in Fig. 14. It is during this knitting of the stocking at three feeds that the stepped high splice S and cradle sole reinforcements and the fashion marks shown in Fig. 2 of 30 the drawings are made.

The construction of the left feed yarn finger is shown in Figs. 8, 9 and 10. This finger 187 is a thin blade beveled at its lower end with the point of the bevel in a forward direction, i. e., 35 in the direction of rotation of the needle cylinder. The body yarn comes through a small hole 188 in the point or toe of the yarn finger, while the splicing yarn for this feed comes through a hole 189 which is above and rearwardly of the main yarn feed hole. The finger is supported on a horizontal rod 190 pivotally supported from a stud 191 forming part of the latch ring 550. On this rod 190 and forming part of the upper end of the finger 187 is a yarn guide bracket 192 45 containing two eyes through which the yarns pass in coming from the bobbin or cone.

When this finger is in its operative position, it lies radially just outside the needle circle. When in its inoperative position it is both raised and moved radially inward. To cause this movement of the yarn finger, there is a tension spring 193 extending from the rod 190 at a point intermediate its ends to a small supporting blade 194 mounted on the latch ring 550. This blade holds 55 its end of the spring radially outward beyond the latch ring (see Fig. 8). The spring tends to keep the yarn finger in its radially outward position and, since the supporting blade 194 is below the rod 190, the tension spring also has a downward 60 pull on the yarn finger.

A thrust rod 460 whose bent upper end underlies the rod 190 is employed to act in opposition to the tension spring 193 and raise this left feed yarn finger. The thrust rod is actuated from 65 cams 501 and 502 shown in Fig. 6. When the thrust rod is on a cam of any height the yarn finger is in its inoperative position. The thrust rod has a tension spring (not shown) tending to keep it in its lower position. Cooperating with 70 this thrust rod is a curved guide 195 shown clearly in Fig. 10. This curved guide is an upstanding plate mounted on top of the latch ring and so located that the rod 190 carrying the yarn finger 187 moves up and down along the inner edge 75

of the guide on the side away from the tension spring 193. This guide therefore determines the exact radial position of the yarn finger at all times. The exact level of the finger when in its operative position is determined by an inwardly projecting shoulder 196 on the guide. In Fig. 10 the lower position of the rod 190 is the operative position of the finger, while the upper or dotted position shows the rod when the finger is in its 10 inoperative position.

When this yarn finger 187 is in its operative position shown in Figs. 9 and 10 (the solid line showing in Fig. 10), the body yarn is being fed to the needles from hole 188 but the splicing yarn 189 is not being fed to the needles from its hole 189 merely because no needles are shown raised for splicing. When the thrust rod 460 is on the cams 501 and 502, the finger is in its inoperative position. The low portions of the cams 501, 502 are to 20 achieve a movement not concerned with three feeds, and when the thrust rod is on such portions the yarn finger is still inoperative. When the thrust rod 460 is down on the main pattern drum itself, as shown in Fig. 6, both yarns are 25 in position to be fed to the needles. Whether or not any splicing is being done depends on the needles. The needles which are not raised by the jacks do not take the splicing yarn.

The yarn finger 200 for the right auxiliary feed feeds yarns from the position 186 in Fig. 14 and is shown in Figs. 8, 11, 12 and 13 of the drawings. The construction of this finger and its controlling parts is different from the finger at the left feed. The finger itself consists of a vertical blade moving in a vertical direction in a bracket 199 forming part of the bracket 14' which supports the dial driving mechanism. The control mechanism is adapted to lift the finger the desired amount and when freed the finger drops under the action of a spring 200' (Fig. 12). The lower end of this finger, instead of being beveled with the holes for the main and splicing yarns one in advance of the other, is straight and thin with the holes one directly above the other, the splicing yarn of course being above the main body yarn. The 45 yarns come to the tip of the finger through yarn brackets 201, 202 fastened on the bracket for the finger. The moving of the yarn finger is initiated through a bell crank lever 203 pivoted on 50 the bracket 14' whose lower arm underlies a stud 204 extending laterally from the upper end of the finger. When it is desired to raise this right auxiliary feed yarn finger to its inoperative position, a direct connection to the main pattern drum through a thrust rod 461 and a wire 205 is employed. The position of the parts when the finger is in this idle position is shown in Fig. 13. One end of this wire is fastened to the upper 55 arm 207 of a 3-way lever 208, with the wire extending rearwardly to a point opposite the arm 207, where the wire passes through a stud 209 extending laterally from the upper end of the arm. On the wire 205 on the side of the stud away from the arm is a screw collar 206. This screw collar is so located as to tip the bell crank lever and raise the finger to its inoperative position when the thrust rod 461 drops to the surface of the main pattern drum. Another arm of this 60 3-way lever is connected to the upper end of the thrust rod 461 so that when the latter moves downwardly the rod 205 is moved rearwardly, raising the lower arm of the bell crank lever 203.

This finger 200 for the right auxiliary feed has 75 two operative positions. In the lowermost posi-

tion both the main and splicing yarns are fed, the main yarn to all the needles and the splicing yarn to needles raised selectively by the jacks, while in the higher feeding or intermediate position the splicing yarn is not fed to any of the 5 needles. This intermediate feeding position is shown in Fig. 12, while the lowermost feeding position, where both yarns go through the needles, is shown in Fig. 11. In order that these feeding positions or levels may be obtained accurately, 10 additional mechanism is employed between the bell crank lever 203 and the lever 208. Beside the rod 205 is a horizontal control lever 210 whose forward end rests on the bracket 14' and through whose rear end passes the stud 209 carried on the 15 upper arm 207. This stud 209 lies in a slot 211 in the lever 210. To the rear end of this control lever 210 is fastened one end of a tension spring 212 whose other end is held rearwardly of the lever by a bracket 213. This bracket is fastened 20 to the stud 209. The lengths of the slot 211 and of the tension spring 212 are such that the tension spring is always exerting a retracting force on the lever 210.

The forward movements of the lever 210 are 25 obtained from the thrust rod 461 acting through the stud 209 on the upper end of the lever 210. Near the forward end of this lever 210 the upper edge of the lever has been cut down to provide two notched levels 214, 215, which surfaces are 30 used to define the exact elevation of the right feed yarn finger 200 in its two operative positions. In the machine shown in the drawings the lower level 215 is rearwardly of the intermediate level 214. The juncture of these two surfaces 214, 215 35 is beveled. The levels determined by these surfaces are transmitted to the bell crank lever 203 and thence to the finger 200 by means of a stud 216 on the bell crank 203. The cams on the main pattern drum for controlling the raising and 40 lowering of this right feed yarn finger are shown in the bottom row of drum cams in Fig. 6 and are identified by the numbers 504 and 505. The cam 504 actuates the finger during the leg, and the cam 505 actuates it during the foot. 45

The timing of the insertion of the yarn fingers will be described in connection with the operation of the machine.

Sinker manipulation at the auxiliary feeds

The construction for withdrawing the sinkers to take the yarn at the two auxiliary feeds is shown in plan in Fig. 18 of the drawings. This figure shows the sinker cap 300 with its lugs 304 which cooperate with the widening picker post 55 400 during reciprocatory knitting, in the usual manner. The withdrawing cam for the sinkers at the left or first auxiliary feed is unitary with a metal spring 493 on the top of the sinker cap. Overlying the free end of this spring is a finger 60 494 extending radially outward beyond the sinker cap and screwed to a rocker arm 495 on a vertical post 496 on the upper bedplate C. The rocking movement of the arm 495 is caused by the depending rocker arm 497 which rests against a pin 65 498 carried in a sleeve on the post 496. This sleeve is free to oscillate on the post 496 and it is unitary with a lever 518 serving to manipulate the stitch cam 543 for this left auxiliary feed and to connect both mechanisms to the thrust rod which actuates 70 them.

The auxiliary sinker withdrawing cam 538 for the right auxiliary feed is carried by a lever 540 pivoted at its front end 303 beside one of the lugs 304 on the sinker cap. The cam 538 itself may 75

- comprise a plate fastened on the upper surface of the lever 540, such plate having a downward extension adapted to enter a slot formed through the cap 300 to withdraw the sinkers in a manner similar to the cam 88 in the Robert W. Scott Patent No. 1,317,897 above referred to. The lever 540 is normally maintained in elevated position by a spring plunger 539 carried in a nipple 541 and pressing against the sinker cap (see Fig. 11).
- 10 The sinker withdrawing cam 538 is pressed downwardly into operative position from the 3-legged lever 208 by means of the arm 212 of said lever which terminates in a boss 213. This boss is located above the end of the lever 540 carrying the cam, and contains a spring-pressed plunger 274 pressing downwardly on the lever. There is a cotter pin in the upper end of this spring-pressed plunger 274 so located that when the thrust rod 461, which controls the position of the 15 20 25 30 35 40 45 50 55 60 65 70 75 main pattern drum, the plunger 274 exerts no downward pressure on the lever 540, thus permitting the compression spring 539 to raise the cam 538 out of its operative position. The adjustment of the arm 212 of the lever 208 and the compression spring 274 is such that the low step of cam 504 shown at the left of the bottom row of cams in Fig. 6 is sufficient to bring the sinker cam into operative position. This also brings yarn finger 200 onto step 214 on lever 210 ready to feed body yarn. However, no feeding takes place until the pattern jacks rise over cam 741 about half a course later.

Knitting cams at the auxiliary feeds

- 35 The arrangement of the knitting cams in the preferred embodiment of my invention is shown in Fig. 7 of the drawings. This figure is a development of the cam cylinder paths looking radially inward into the machine.

40 At the main knitting point there are the usual top center cam 357, leading stitch cam 361 and following stitch cam 360. The leading stitch cam 361 is retractable in any well-known manner. 45 The cam ring 271 raises the needles after they pass the knocking-over point at the main feed unless the pattern jacks are raising them, but the cam ring does not raise them far enough to clear the latches. A clearing cam 542 for the first or 50 left auxiliary feed is therefore used, which can be retracted and inserted in a manner to be described subsequently, and a stitch cam 543 takes the needles as they come from the clearing cam and lowers them to the knocking-over point. A 55 stationary raising cam 544 is located just below the end of the stitch cam 543 but this raises the needles only part way to the clearing point.

60 The left feed clearing cam 542 is mounted on the left stitch cam bracket 511 and is movable into and out of operative relation with the needle butts. When in its operative position it engages all the needle butts. It is in this position when knitting three feeds. A tension spring 512 between the bracket and the cam normally tends to 65 keep the cam retracted in its inactive position. Opposing the force of this spring are means controlled by a thrust rod 462 from the main pattern drum (see Fig. 1). There is a bell crank lever 513 mounted on the post 514 on the upper bedplate C, one arm of which lever lies at the rear of the cam 542. The other end of this lever 513 is pivotally connected to a rod 515 which in turn is fastened to a rocker arm 516 of a bell crank lever pivotally mounted on the shaft 716 passing through the 70 latch ring post 401. This lever also has an arm 75

517 linked to the upper end of the thrust rod 462, which thrust rod is actuated by drum cams 506, 507 (see Fig. 6). When the thrust rod 462 rides up on cam 506, this left feed clearing cam 542 is put into operation during the leg, and when the thrust rod rides up on drum cam 507 the clearing cam is put into operation during the making of the foot. The leading ends of drum cams 506 and 507 are stepped in order that the clearing cam for the left feed may be introduced in stages, as will be described later.

5 10 15 20 25 30 35 40 45 50 55 60 65 70 75 80 85 90 95 100 In the example shown in Fig. 7, a vertically movable cam 549 in the gate then raises the needles further when they leave the cam 544. Except during splicing or when making a float stitch pattern, it does not raise the needles enough to clear. The right feed stitch cam 545 can be located just after the usual switch cam 415 (Fig. 7). Upon reaching the bottom of this right auxiliary feed stitch cam, the needle butts are met by a small stationary raising cam 546 after which they come in contact with a raising edge 547 on the cam ring. Thence they pass to another clearing cam 548 which raises all the butts (except the .220) a little higher than the cam ring would raise them. The path of needle butts just described is the path taken during three feed knitting by the needles which take only the body yarn. The mechanism for manipulating such of the knitting cams as are movable will now be set forth.

20 25 30 35 40 45 50 55 60 65 70 75 80 85 90 95 100 The left feed stitch cam 543 is retractable and is controlled from the same drum cams as the left feed sinker withdrawing cam fastened to spring 493. This stitch cam 543 is adjusted by a screw fastened in one leg 624 of a crank arm 518 on the vertical post 496. The crank arm also carries the pin 498 by which the sinker cam is controlled. The connection between this crank arm 518 and its operating lever 463 consists of a link 519 connecting the crank to a rocker lever 520 pivoted on the vertical post 514. A rod 521 connects the longer portion of the lever 520 to the lever 463. High drum cams 508 and 509 under the foot of this lever serve to actuate the left feed stitch cam 543 and the sinker cam 538 during the leg and foot, respectively.

20 25 30 35 40 45 50 55 60 65 70 75 80 85 90 95 100 The stationary raising cam 544 just below the end of the stitch cam 543 is mounted on the cam ring 271.

20 25 30 35 40 45 50 55 60 65 70 75 80 85 90 95 100 Turning now to the knitting cams for the right auxiliary feed, we find that many of the cams and their control connections to the thrust rods are carried by a knitting cam bracket 618 on the upper bedplate C near the rear of the machine. The forward end of a slide in this bracket 618 carries the right feed stitch cam 545 and the raising cam 546, both of these cams being retractable. Cam 548 is pivoted on the cam ring with a shoulder screw. All three cams are actuated from one thrust rod 466 which serves to push them into operative position, the cams being spring-pressed so that their normal position is out of operative relation with the needle butts. The mechanism between the thrust rod and these cams is also carried by the bracket 618 and consists of the following parts. Contacting the backs of the slide is one arm of a bell crank lever 619 pivoted on a vertical pin or lug 622 of the bracket 618. The other arm has an adjustable contact with a rocker arm 520 pivoted on a horizontal axis on the bracket 618. The end of this rocker arm overlies an extension plate 621 fastened on the upper end of the thrust rod 465. If desired this thrust rod can be the one which reads the cams on the 70 75 80 85 90 95 100

- main pattern drum, but in the machine here in question it is preferred to use a drum cam path on the other side of the machine, i. e., the left side, so it is necessary to have a horizontal bridge 5 member 623 underlie the plate 621. The drum cams are identified by the numbers 631 and 632. The small drum cam preceding cam 631 is used during makeup. The low cam after 632 is used during the heel.
- Owing to the fact that the yarn fingers 187 and 200 for the left and right feeds come down from above the needles just outside the needle circle, they are in positions where they would be hit by any flying needle latches. There will be flying latches if, for any reason, there should be a press-off, and therefore means are provided to stop the machine if there are any flying latches. These means consist of a detector located just above the sinker cap and moved into and out of operative relation with the needles by the controls for the right feed stitch cam. The connection between the controls for the stitch cam and this detector consists of an upwardly extending arm 624 mounted on the bell crank lever 619. The detector itself consists of a long needle 625. The arm 624 is adapted to push this needle into its operative position (Fig. 18). In order to gain access to the needle circle at a sufficiently low level at this point on the circumference of the machine, the pivoted lever 540 carrying the right feed sinker cam 538 is humped upwardly at 626 so that the needle 625 may pass freely thereunder at all times. The detector needle is supported by a flat U-shaped bracket 627, the needle passing through each leg of the bracket. A compression spring 628 is coiled around the needle between the two legs of this bracket, and at the rear end of the spring between the arms of the bracket a collar 629 is fastened on the needle. When the needle is pushed forward into its operative position the collar 629 compresses the spring 628 against the forward arm of the bracket, and when the needle is released by the arm 624 the spring pulls it back out of operative relation with the needles. The bracket 627 is pivotally supported by a screw 630 intermediate the ends of the bracket and extending downwardly into a vertical support rod 640 mounted on any convenient part of the machine (see Figs. 1 and 11).
- Underneath the screw 630 on top of this supporting rod 640 lies a stationary plate 641 carrying the trip mechanism operated by the detector. The needle 625 and its bracket 627 are normally held with the needle pointing into the needle circle by a tension spring 642 extending from the inner end of the bracket to a small eye on the cover for the vertical dial driving shaft 18 (see Fig. 13). If the point of the detector needle 625 should be hit by a latch of a knitting needle, the needle 625 and its bracket would pivot about the screw 630 thus swinging the rear end of the bracket toward the front of the machine. Except when the bracket is thus swung by a flying latch, there is a small bent arm 643 resting against the rear leg of the bracket 627. This arm 643 is screwed to the upper end of a vertical shaft 644 extending downwardly to the lower bedplate B (Fig. 4). At this point this rod takes into a stationary support 645 but in such manner that the shaft 644 can revolve without turning the support. Attached to the vertical control shaft 644 just above its support 645 is a blade 646 extending laterally, whose free end is attached to a tension spring 647 anchored to the support 645. This spring is so located that its tension causes the bent arm 643 on the upper end of the control shaft to press constantly against the bracket 627. When the detector needle strikes a flying latch and swings the bracket away from the arm 643, that arm is released and the control shaft 644 will turn. In direct line with the resulting path of movement of the blade 646 is a trip wire 648 having a collar 649 thereon, which wire goes to any of the usual stop motions. The release of the bent arm 643 at the upper end of the vertical control shaft 644 causes the blade 646 to pull on the collar 649, thus tripping the stop motion.
- In Fig. 5 there is shown the arrangement of the needles in the needle cylinder in accordance with the length of their butts. There are five lengths 15 of butts, the so-called .220, .270, .300, .338 and .390. These butts provide the proper timed beginning and stopping of these various kinds of knitting. As shown in Fig. 5, there is a group of .220 needles n' flanked on each side by a group of .270 needles n^2 , n^{22} . The arrow shows the direction of rotation of the needles. The group n^2 precedes the .220 group n' . In the group n^{22} is a .220 needle for fashion marks. The .270 group n^2 is preceded by a group of .300 needles n^3 , and 20 the .270 group n^{22} is followed by a .300 group n^{33} . These groups occupy one semi-circle of the needle cylinder. The other half comprises a group at either side adjacent the .300 needle groups just mentioned, composed of needles having .338 butts 25 and identified as n^4 and n^{44} , respectively. These groups in turn are each adjacent a group of .390 butted needles n^5 and n^{55} , respectively. In between these two groups of .390 needles is a group of .338 needles n^6 . The relative lengths of the 30 butts are suggested in Fig. 5.
- Yarn cutting and clamping*
- The mechanism for handling yarns which are taken out of action and yarns which are put back 40 into action is shown in Figs. 14, 15, 16 and 17 of the drawings. In Figs. 14, 15 and 16 the dial cap D' is shown, but for simplicity the dial itself and the transfer bits or other knitting elements therein are omitted. Referring first to Fig. 14, it will 45 be seen that the cutting and clamping device and the guards accompanying it are mounted on the dial cap. The periphery of this dial cap D' is cut down all around the cap in view of the various operations and positions necessary in cutting, 50 mounting and feeding various yarns. On top of the dial cap are the usual main yarn clamp c and a main yarn cutter c'. This main yarn cutter and an auxiliary yarn cutter are operated by the mechanism shown in Fig. 17. Thus from the 55 moving blade of the main yarn cutter a wire 57 extends upwardly to a bell crank lever 58 pivoted on the latch ring and whose other arm overlies the upper end of a suitable thrust rod 59. It is not desired to cut and clamp yarns from all three 60 feeds in the one clamp and cutter, and in addition to the usual clamp c and cutter c', a second clamp 69 and cutter 72 are provided in the dial cap at a point about 30° after the main cutter. The main yarn clamp c and cutter c' serve to 65 clamp and cut not only idled yarn from the throat plate 559 but also idled yarns from the right feeding point 186. A wire 63 from the auxiliary cutter 72 is hooked to the end of the bell crank lever 58, and the bell crank lever is spring-70 pressed upwardly by a spring 64.
- In order to be sure that the floats of yarn which occur during splicing go under the dial rather than over, shoulders or notches in the circumference of the dial can be used. In the ma- 75

chine illustrated in the drawings there is one notch 66. Idled yarns from the right feeding point 186 pass under a guard 67 but on top of the dial cap, thence around the dial cam blocks indicated by dotted lines, under the guard 68, and thence to the main clamp and cutter. The idled yarns from the throat plate pass under the guard 68 and on top of the cap and thence to the main clamp and cutter. In order that idled yarns from the left feeding point 185 may not get into the main cutter and thus be cut off without being clamped, means must be provided which consist of an extension guard 76 on the movable blade of the main cutter c'. This guard is so shaped and of such length that at no time can idled yarns from the left auxiliary feeding point 185 get into the main yarn cutter. The guard essentially consists of an arm extending outwardly from the cutter blade to the periphery of the dial cap and then counterclockwise along the edge of the cap past the feeding point 185. Underneath guard 76 is a guide plate 73 located above the cap 74, and its purpose is to guide the main yarns into the cutter c'. The plate 73 extends around to a position opposite the auxiliary cutter 72 and carries on it the auxiliary clamp 69.

Needle selection for splicing

One of the big problems in a machine of this type is to find room for the mechanism to make variable splicing or other selections so that knitting can be done at all three feeds. The present illustration of the invention is one in which the splicing is varied, i. e., a stepped high splice and stepped cradle sole reinforcement are made. The customary way of making such a construction is to select the needles by means of pattern jacks for each course of the knitting, but it is physically impossible in a machine of this type to select three times for each revolution of the needle cylinder. To get such variable splicing in the machine, I have devised a construction in which one selection by the pattern jacks is made to serve for three courses of knitted fabric, and then all movements caused by such selection are nullified and a new selection is made. The selections are caused by means of pattern jacks selected from a trick wheel.

I will first describe the trick wheel and its control. Referring to Fig. 4, it will be seen that there is the usual trick wheel 800 with teeth on a ratchet wheel 804 underneath same adapted to permit the trick wheel to be racked around by virtue of a pawl 803 reciprocated in any usual manner. In order to idle the pawl when it is desired to have the trick wheel stand still, there is the usual idling plate 812 with tension spring 806 normally holding the idling plate beyond and out of contact with the pawl 803. The circumference of the trick wheel is prepared for selection in the customary manner and there is the usual set of reader cams 820 on a vertical post 821, each having a tail adapted to read its own particular level of butts 810 on the trick wheel. Where a butt has been broken off, the tail drops to the surface of the trick wheel by virtue of a tension spring 843 on one end of the reader cam, and the other end of the reader cam then lies against the surface of the cylinder carrying the jacks and presses inwardly the lower end of any pattern jack 736 which presents a butt to that particular reader cam. The construction of these pattern jacks forms the subject-matter of the above-mentioned patent to Ivan W. Grothey No. 1,678,385. The reader cams

820 can be idled in groups. Thus an upper group of reader cams can be idled from a lever 831 controlled by pattern drum cams 832 and 833. This lever has a pull wire 830 connecting it to a jack selector lever 829 pivoted on the lower bedplate 5 B. This lever holds the reader cams 820 out of operative relation with the trick wheel and the pattern jacks when the thrust rod 831 rides up on a high cam on the main pattern drum. A similar lower jack selector control lever can also be used. The construction is also found in the patent to A. E. Page No. 1,969,853, above referred to.

It will be noted that the process of selection and subsequent raising of the pattern jacks 736 involves first the rocking outwardly of the lower end of the jacks by pushing inwardly on the upper end. The subsequent pushing inwardly of the jacks which it is desired shall not act on their needles then follows, and the jacks whose lower ends are still out are raised and act on their needles. The pushing outwardly of the lower ends of all of the jacks in order that they may be selected is caused by a resetting cam 747 located on a level opposite the upper ends of the pattern jacks 736, at a point slightly prior to the time 20 when the reader cams 820 act on the butts of the jacks. This selecting of jacks for the three courses of knitting takes place between the left feed point 185 and the right feed point 186, as can be seen by reference to Fig. 7 of the drawings. 30 The description of the movements of the pattern jacks, needles, etc. will be with relation to the preferred embodiment shown in Fig. 7, until otherwise indicated. As in the case of the Page Patent No. 1,969,853, there are intermediate jacks 732 between the pattern jacks 736 and the needles N. The paths of such pattern jacks 736, intermediate jacks 732 and needles N, as are selected for splicing, are marked in solid lines on Fig. 7. (The tails on the lower ends of the pattern jacks are omitted in Figs. 7 and 20 to 40 make the manipulations more clear.) The paths of the butts of needles which are not selected for splicing are indicated in dotted lines. The path of the needles is different when no needles at all are splicing. The differences in the path of travel of the needle butts at that time from the path of the splicing needle butts when splicing, are shown in Fig. 7 by the dotted and the dot-and-dash lines.

Jack selection

Selection of needles by jacks is used for splicing and, in some instances, for knitting. When used for splicing the finger is in its lowermost position; when used for knitting the body yarn only, 55 the finger is raised to an intermediate position. This latter occurs at the right feed only.

When the lower end or operating butt 733 (Fig. 21) of a pattern jack is rocked out in order that it may select its needle, it meets a raising cam 60 741 (Fig. 7) prior to the point where the yarn from the right feed reaches the needles. The pattern jack 736 riding up this cam 741 raises its intermediate jacks 732 and shortly thereafter the jack moves up into the region where the needle butt is located and raises it still higher. At this higher level the needle takes not only the main yarn being fed from the lower hole in yarn finger 200, but also the splicing yarn being fed from the upper hole in that finger if the finger is 70 in its lowermost position. At this point the needle comes under the stitch cam 545 and is pushed downwardly, while the intermediate jack is pushed down an exactly similar incline 795 on the lower edge of the cam ring 271. In this way 75

the intermediate jacks push the pattern jacks downwardly again to their normal level. By locating this surface 195 properly with relation to the pattern jacks it is possible for the pattern jacks to maintain their grip on the cam 741 so that only the operating butts 133 of the selected jacks remain in their outward position, ready for use again. As soon as the needles have been cleared by cams 546 and 548 the pattern jacks 10 are raised by a second raising cam 741' which raises the intermediate jacks 732 once more and they pick up the needles near the top of their movement and raise them above the clear level to a high level which enables them to take the 15 splicing yarn from the yarn finger F' in the throat plate if it is in action, as well as the main yarn from the finger F. Once again the intermediate jacks are pushed down by a surface 796 on the lower edge of the cam ring and there push the 20 pattern jacks down. For the third course of stitches the same procedure is followed, the pattern jacks riding up a raising cam 741'', raising intermediate jacks and picking up the needles near the top of the movement to raise them so 25 that they will take the splicing yarn from the hole 189 in the finger 187 at the left or first auxiliary feed as well as the main or body yarns of the hole 188. The intermediate jacks are then forced down by surface 797 on the lower edge of 30 the cam ring which also returns the pattern jacks to their normal level. Thereafter the jacks are reset by cam 747, thereby destroying the selection used in the first three courses, and the machine is ready to make a new selection and carry it 35 through three more feeds.

Another intricate matter in the timing of the machine relates to the beginning and ending of the knitting at the two auxiliary feeds. It has been discovered that when starting an additional feed in a machine, the newly inserted yarn has nothing to tie it in and therefore it leaves an eyelet hole. In order to cover up this eyelet hole, the machine is so arranged that the eyelet hole always occurs at the point where it will be covered up by the mock seam. The needle which is located at this point in the knitting is the first one of the .270 group n^2 which in the knitting comes right after the .220 needle group n^1 . I will first describe how this needle is caused to be the first to knit at the left feed. The selection is made by means of the clearing cam 542 in cooperation with the various lengths of needle butts. The drum cam 506 (Fig. 6) is so located on the main pattern drum that during the rack which 50 actually starts the two auxiliary feeds into action the cam will start insertion of the clearing cam 542 while the group of .220 needles n^1 are opposite the cam. The thrust rod 462 moves up onto the low step at the beginning of the drum cam 506 55 while the .220 needles n^1 are passing. This serves to contact all the butts except the .220 butts. As soon as the cylinder has revolved sufficiently to bring some of the .270 butts of the group n^2 opposite the cam 542, the thrust rod, continuing its movement, rides up onto the high portion of the cam 506, completing the insertion of the clearing cam so that thereafter it will clear all needles.

In this way the first needle to be cleared and therefore the first to be raised high enough to 70 take any yarn at the left feed will be the first needle of the .270 group n^2 . The left feed yarn finger 187 is in its operative position at this moment on the low end of the cam 501 just prior to the position shown in Fig. 6. In this position the 75 main yarn coming through the hole 188 in the

lower end of the finger 187 is the only one presented to the needles which are cleared by the cam 542, because no needles are being raised by the jacks.

During the making of fabric which contains no 5 sectional splicing such as the high splice or cradle sole reinforcement, the manipulations are quite different from those employed when there is sectional splicing. When it is desired to begin knitting at the right feed, no sectional splicing 10 is taking place. The yarn finger 200 is in its intermediate position shown in Fig. 12 and the needles which are to take the body yarn at this right feed are all raised by their packs to take the yarn. During this unreinforced knitting at 15 the right feed the pattern jack pushout cam 747 pushes out all the packs so that all the needles are raised. In order to start knitting on the first 20 of the following .270 needle group n^2 , a reader cam 820 is employed to push radially inward the lower ends of the pattern jacks under the .220 25 needle group n^1 , so that the first needle to be raised as knitting is begun is the first of the .270 group n^2 . The pawl 803 then racks the trick wheel 800 and the reader cam 820 is retracted, causing the .220 pattern jacks to be out on succeeding revolutions along with the others.

When knitting with sectional splicing at the right feed, the clearing of the needles is not done by the pattern jacks but by the clearing cams acting on needle butts. To accomplish this, the gate cam 549 is raised into its operative position shown in Fig. 7 in full lines. This elevates all the needles to the clear level. Thereafter the pattern jacks raise only those needles which are to 35 take the reinforcing yarn, the selection being made by the reader cams 820 in the ordinary manner. The yarn finger is put in its lowermost position to present the splicing yarn to the selected needles.

It is desired to end the knitting at the auxiliary feeds on an exact needle and preferably the same needle at both feeds. The machine is so arranged that the last needle to knit is the last of the .270 group n^2 which precede the .220 40 needle group n^1 . At the right feed the right stitch cam 545 is withdrawn in stages. The stitch cam is partially withdrawn till out of the path of .220 butts while the .270 needles n^2 just ahead of the .220 group n^1 are passing the cam. 45 In this way the last needle to knit is the last needle of the .270 group n^2 preceding the .220's. As soon as the right hand stitch cam is opposite the .220 needles n^1 it completes its withdrawal.

It is also necessary to stop the selection of needles by the jacks, and to do this the resetting cam 747 is pulled out of operative relation with the butts. This is timed to take place when the cam is at the leading group of .390 needle 60 butts n^5 , and stops the splicing at that point on the right feed. Simultaneously there is an idling lever 743 which pushes radially inward the butts of the pattern jacks 736 which have been selected for splicing at the beginning of the .270 group 65 n^2 , so that except for the first few splicing jacks the remainder do not ride up the cam 741'' at the left feed.

The left feed jack idling lever 743 is pivoted on the lower bedplate B by a bracket 373 and is 70 held at the proper level by a link 374 attached to the cam not far from its operative end. The exact inward position of the cam is determined by a tension spring 375 and a slot and screw arm arrangement 379. One end of this lever 75

- overlies the beveled upper end of the thrust rod **468**, the raising and lowering of the thrust rod determining the movements of the cam into and out of operative relation with the operating butts **5** **733** at the lower end of the pattern jacks. This serves to stop the splicing at the left feed. The idling lever **743** can be controlled from the main pattern drum in much the same manner as the resetting cam **741**.
- 10** At this point the left feed clearing cam **542** also withdraws, which stops clearing of the loops of any needles which were not raised by jacks. This withdrawal of the clearing cam **542** takes place while the first group of .300 needles **n³** are passing. The needles which are not cleared by the cam **542** remain at the tuck level and miss the splicing yarn but take the main yarns. After a number of uncleared needles have been drawn down by the stitch cam **543** to lay the main yarn **15** under the sinkers, the left feed yarn guide **200** is lifted out of action at the end of the leading group of .270 needles **n²** and simultaneously the stitch cam **543** is withdrawn.
- In order that the machine—which is adapted **20** to start up the knitting from the bare needles—may make up, and subsequently may be able to make tuck stitches such for instance as are required in making fashion marks **41**, it is necessary that the needles in the machine be able to travel uninterruptedly by the locations of the right and left feeds. For illustrative purposes the mechanism to accomplish this will be described in connection with the making of fashion marks. The fashion marks needles have .220 **25** butts and are located in the .220 needle group **n'** and in the following group of .270 needles **n²²**. Since the fashion marks **41** are being made while the machine is knitting at all three feeds, and we desire to have two pairs of tuck stitches **30** one below the other, the machine is arranged to tuck for two courses and then knit one course. The tucking occurs at the right feed and the main feed. The right stitch cam **361** at the main feed is withdrawn during the making of fashion marks and preferably during all the time **35** that the three feeds are working, and the fashion marks control is obtained from the pattern jacks **736**. It is essential also with the embodiment shown in these drawings that the right stitch cam **361** at the main feed be withdrawn during the making of the high splice and sole **40** reinforcements. At the right feed all the jacks raise their needles to the clearing point except those which are to make the fashion marks. One of the reader cams **820** has pushed inwardly **45** the lower ends of the pattern jacks **736** underlying the fashion marks tucking needles and therefore those needles are not raised to the clearing point but approach the stitch cam **545** at the right feed at the level at which they are **50** left by the gate cam **549** which is in its lower position. This gate cam **549** stays in its lowermost position throughout the knitting at three feeds until the high splice is reached. Thus at **55** the right feed all the needles knit except the fashion marks needles which tuck. Coming out from under this right feed stitch cam **545**, all the needles are raised by cam **546** and the edge **547** of the cam ring **271**, but thereafter the tucking needles are again treated differently in **60** order that they may tuck at the main feed. The clearing cam **548** when inserted in its operative position does not extend close enough to the needle cylinder to catch the needles with .220 butts, and therefore it raises only needles with butts **65** longer than .220. This allows the fashion marks **70** tucking needles to travel ahead at the tucking level, all others (including the .220 butts other than those tucked) being cleared by their jacks. Shortly thereafter the pattern jacks underlying all of the needles except the fashion marks tucking needles will ride up their raising cam **741**, and thus raise all the needles (except the fashion marks tucking needles) to the clear point. Coming out from under the stitch cam **360** at the main feed, all the needles are cleared by the **10** clearing cam **542** and the tuck stitches are knit off under the stitch cam **543**.
- The gate cam **549** is controlled by drum cams **522**, **523**, **524** and **525** on the main pattern drum through the intermediary of a curved cam plate **802** around the cam ring, a tension spring **813** extending between the forward end of the curved plate **802** and post **400** and tending to pull the cam plate so that the cam **549** can drop to its **15** lower position. The plate **802** is connected to its thrust rod **467** by a wire **801**.
- The construction of heel shown in Fig. 2—assuming that the stocking is being knit from top to toe—is made as follows. First the usual narrowing courses are made and then an extra gusset is made in the point of the heel by putting in a **20** few of the main widening courses and then narrowing again to the same number of courses that were widened. In these respects the heel is like the patent to W. E. Smith No. 1,216,374. Thereafter, instead of inserting the remainder of the main widening courses in the usual manner, the knitting of the sole is begun at once, using a lesser number of wales on the sole side of the suture than on the narrowed side of the suture. **25** In this connection reference is made to the Sheppard Patent No. 1,932,292.
- Modification of Figs. 20 and 21*
- In order to make a machine which will run a **30** little more freely, a modification has been invented in which the jack cams, cam cylinder and the pattern jacks have been changed as shown in Figs. 20 and 21. In this modification the pattern jack itself rises only for every third **35** course of the knitting, and the pattern jack itself is modified somewhat. It will be observed that it has the usual operating butt **733** and selecting butts **738**, and also a main lowering butt **938** located just above the butts **738** and extending outwardly beyond the pattern butt. At the upper **40** end the jack is shaped in an unusual manner. The novel construction at the upper end of the pattern jack and which cooperates with certain cam formations in a manner which will be described, consists of a notch or shoulder **928** on the butt or outer side of the pattern jack extending downwardly from the upper end of the jack a distance of say $\frac{1}{8}$ ".
- In Fig. 20 the jacks and needles are shown **45** taking the paths pursued by the splicing jacks and needles, i. e., those which are raised to take the splicing yarn at the three feeds. The pattern jacks thus selected by the reading cams **820** are elevated on the raising cam **941** in the **50** same manner as in the embodiment of Fig. 7, and when they reach the top of their rise it becomes necessary to separate them from the intermediate jacks **732** in order that the intermediate jacks only may thereafter raise the needles at the two **55** other feeds. This separation is obtained by a cam **746** underlying the cam ring **271** and spaced from the lower edge thereof a distance sufficient to permit the operating butts of the intermediate jacks to pass therebetween. The leading **60**

point of this cam is at such an elevation that it meets the pattern jack 736 and the intermediate jack 732 in between the two jacks, i. e., below the butt of the intermediate jack 732 and just above the notch or shoulder 928 on the pattern jack. The upper end of the pattern jack is not rocked out far enough to bring the top of the jack above the shoulder out of the cylinder slot. In this way the cam is able to divide the two kinds of jacks, 10 the intermediate jacks rising up the cam to an elevation which enables the needles to take the splicing yarn in the same manner as shown in Fig. 7. Thus the pattern jack can be lowered and the intermediate jack raised by a cam without causing 15 a smash-up.

When the pattern jacks have been returned part way to their normal level, the job of lowering them is turned over to another butt and another cam. The cam which now takes over the 20 job of finishing the lowering of the pattern jacks is a triangular cam 742 acting on the butt 938, just below the rocking point of the jack. In this way the pattern jacks are taken away from the cam surface which separated the pattern jacks from the intermediate jacks. The cam 742 lowers the pattern jacks just a little further than their proper level for selection by reader cams 820 in order that they may be accurately positioned later by another raising cam (not shown). The cam adjacent cam 742 is to perform this function on the last reverse movement coming off the heel. Similar means for accurate positioning can be used in the mechanism of Fig. 7.

In the meantime the intermediate jacks having been raised to their highest level by the raising surface of the cam 746, they come against a lowering edge 996 of the cam ring 271' and are driven down to a level just a bit lower than the knocking-over point of the needles. While coming down this slope 996 the intermediate jacks 40 are sufficiently low to be separated a slight distance from the butts of their associated needles. Immediately after reaching the knocking-over point at the bottom of stitch cam 545 at the right feed, the needles are raised by a cam 546, as in the case of Fig. 7, then the raising edge of the cam ring 271' and then the clearing cam 548'.

Just as the needle butts are leaving the raising cam 546 the butts of the intermediate jacks 732 start up a raising cam 941' located underneath the cam ring, which raises the needles to a sufficiently high level to take both the splicing and main yarns at the main feed. As soon as the intermediate jacks have pushed the needles to this level—which is the same level as in the preferred form of Fig. 7—they come in contact with a lowering surface 997 on the lower edge of the cam ring and once more are pushed down to their normal level. They travel along at this 55 level while the needles pass under the top center cam 357 and the stitch cam 360 and are started on their upward path by a raising cam.

Then the intermediate jacks meet another raising cam 941'' and once more push the needles 60 upward to the splicing level. The needles that are not so raised are cleared by a cam 542'. They are pulled down for the last time by lowering edge 998 of the cam ring, while the needles are travelling down the stitch cam 543 at the 65 left feed, with a slight space between the needle butts and the tops of the jacks, as in the case of the situation at the right feed. After leaving the stitch cam 543 they are started upward by a cam 544' and thence to the cam 549, as in Fig. 7. The 70 movable cams in the embodiment of Fig. 20 are

controlled in a manner similar to those of the embodiment of Fig. 7.

Operation of the machine

The construction of the machine having been described, the operation of the machine will now be set forth, directing attention first to Figs. 1 to 19. In describing the operation, I will describe only so much as relates directly to the two auxiliary feeds and the parts modified in connection therewith. The machine will be described operating with three feeds during the leg and foot, but not during the welt, transfer, heel or toe.

Owing to the fact that the various changes are made from the main pattern drum which is racked only intermittently, and to the fact that the various elements have to be introduced in a certain timed relation to all the other parts in order that the two auxiliary feeds may begin at 15 the desired point, it is necessary to begin preparation for the three feed knitting early in the operation of the machine. Thus when the machine is making a Model K inturned welt, the first movement of the parts directly involved with the 20 two auxiliary feeds occurs at the beginning of the rack of the main pattern drum preparatory to transferring the loops on the bits to turn the welt. The trick wheel pawl 803 is idling on the surface 812 and all the reader cams 820 are retracted out of operative relation with the pattern jacks 736. This preliminary transfer rack starts on a low cam surface on the main pattern chain and during the four courses of knitting while the main pawl is on its low surface nothing relating 25 directly to the two auxiliary feeds takes place, the only movements being to lower the clearing cam 549 and insert the stitch cam 361.

When at the end of the four courses the pattern chain is racked ahead and puts the pawl on a high portion of the link, the first operations 30 directly relating to the three feeds takes place. As soon as the pattern chain pushes the pawl controller onto the high portion of the link, the main pawl begins to make a long rack on the main rack wheel. When the main rack wheel starts to turn, the main pattern drum of course 35 also starts to turn and the transfer bits in the dial are pushed out. Immediately thereafter the thrust rod 463 rides up onto the cam 508 on the main pattern drum, which moves the left feed 40 stitch cam 543 into action and the corresponding sinker withdrawing cam carried by the spring 45 493. The left feed stitch cam 543 completes its inward movement while over the .270 needle group n^{22} . It is necessary to introduce part of the auxiliary feeds at this point because there is no 50 time to introduce both the extra feeds in their entirety in proper timed sequence at any later time in the operation of the machine. The time of introduction of the stitch cam 543 is such that it is introduced while the .220 needle group n' is 55 passing. This occurs while the lower end of the thrust rod 463 is passing over the low step at the beginning of the drum cam 508. By the time 60 the thrust rod has ridden up onto the top of the cam 508, the following group of .270 needles n^{22} are opposite the stitch cam and the stitch cam goes all the way in. It might be noted at this 65 point, however, that the auxiliary yarns are not presented to the needles and the needles have not been cleared, so that no stitches are drawn and no stitches knocked over at this feed as yet.

While the main pawl controller is still on the high portion of the pattern chain link, the main

pawl makes an auxiliary rack, causing certain additional operations relating to the auxiliary feeds. One of the additional manipulations taking place at this time is the movement of the jack 5 resetting cam 747 out of operative relation with the upper ends of the pattern jacks. This occurs when a thrust rod 464 rides down off drum cam 526 to the surface of the pattern drum, causing the arm 798 to swing as it rides up the bevel at the 10 top of the thrust rod, and move the cam 747 out of operative relation with the pattern jacks. As this auxiliary rack comes to an end, the left feed yarn guide 187 is dropped to its operative position shown in Figs. 9 and 10, by the thrust rod 460 15 riding off the high portion of cam 501 to the low portion thereof. In this operative position it is ready to feed yarns to any needles which may be raised sufficiently to take the yarn. The tension spring 193 holds the finger radially outward 20 against the plate 195 to its correct radial position. Although this finger is thus in an operative position, no knitting wave has been created at this point, so that as yet no body yarn can be fed to any needles at this feed. But it will be observed 25 that at each of the feeds some of the preparatory movements have taken place well in advance of the time when they are needed, but they are such that it does not interfere with the operation of the machine and reduces the number of timed 30 operations actually necessary when beginning the two feed knitting. The right feed clearing cam 549 is still in its lower position.

The preparations all having been made, and by taking advantage of the racking which occurred at the time of transfer, the machine can now knit as many plain courses at the main feed alone as may be desired. Thus, for instance, twenty-eight courses can be made at this time before starting the rack which starts the two 40 auxiliary feeds.

The rack which causes the machine to start the two auxiliary feeds performs principally functions relating to three feeds. It may however introduce the main yarn at the main feed. 45 On this rack of the main pattern drum the clearing cam 542 located just prior to the left feed stitch cam 543 is moved into operative position while over the .220 needles n' and begins to act on the first of the .270 needles in the following 50 group n^{22} . This introduction of the left feed clearing cam 542 is caused by the stepped drum cam 506 acting on the thrust rod 462, rocker arms 516, 517, rod 515 and bell crank lever 513. This clearing cam raises the needles a sufficient distance to take the body yarn from the left auxiliary yarn finger but not the splicing yarn. When the first of the .270 needle group n^{22} takes 55 this body yarn from the left feed point 185, it is lying over the guard 13 to the clamp and cutter 60 69, 72.

The insertion of the right feed stitch cam 545 starts at the same time—just when the center .338 needle group n^6 are opposite the stitch cam, and the insertion occurring at the end of this 65 group of needles, it becomes effective in the .390 group n^5 which follow the center .338 group, and completing its insertion there, continues to take all needles. Therefore the first needle to be drawn down by the right stitch cam 545 is the 70 first needle in the group of .390 needles n^5 . This insertion is caused by drum cam 631 acting on the lower end of thrust rod 466 which in turn acts on the bridge thrust rod 465, extension plate 621, rocker arm 620 and the bell crank lever 619. 75 The extension 624 on the lever 619 causes move-

ment into operative position of the flying latch detector needles 625 at the last of the inward movement of the right feed stitch cam.

As already explained, it is desirable that both the yarn feeds begin knitting at the same needle 5 and that that needle should be in a location where the mock seam will cover the eyelets which they produce in the fabric. The first needle of the following .270 group n^{22} is the needle where knitting should begin to accomplish this, and 10 how this is accomplished at the left feed has already been explained. It being impossible to introduce the stitch cam and yarn fingers in such timed relation as to have this happen at the right feed as well as the left feed, the raising of 15 the needles to the point where they will take the yarn at this feed is availed of to select the desired needle for beginning knitting. This can be accomplished through the jack selecting mechanism. As already stated, the gate clearing cam 20 549 is not in its raised position and therefore the needle butts come toward the right feed stitch cam below the clear level. The thrust rod 464 is raised by drum cam 527, causing insertion of the jack resetting cam 747 into its operative position 25 where it pushes out the lower ends of all the jacks. In order that the first of the following .270 needles n^{22} may be the first ones to get the yarn at this feed, the lower ends of the .220 needle jacks must be pushed radially inward, and this 30 is accomplished by dropping into action at this point the lowermost of the reader cams 820. Preferably this selector finger has been in its operative position since the auxiliary rack during the transfer, but ineffective because the resetting 35 cam 747 was not in operative position. The resetting cam 747 is effective if its thrust rod is up on a cam of any height. This selector finger pushes in all the jacks of the .220 needle group n' . In the meantime the right auxiliary finger 40 200 is dropped to its intermediate active position where it is ready to feed the body yarn but not the splicing yarn to the needles raised by the jacks. This is accomplished when the thrust rod 461 rides up onto the low surface of the drum 45 cam 504. This movement not only causes the insertion of the sinker withdrawing cam 538 but also pushes forward the wire 205, dropping the stud 216 onto the high cam surface 214 on the control lever 210, thereby putting the right yarn 50 finger in its intermediate position (see Fig. 12). In this way the first of the .270 needles is the first to get the yarn and to knit at the right feed.

It is necessary to insure that the .220 needle group n' will be able to take this yarn on succeeding revolutions of the three feed operation, and to this end the trick wheel 800 is racked by its pawl 803. As soon as the drum begins to turn, the lower selector finger 820 which has been resting in a buttless spot on the drum since the 60 transfer rack, moves to a butt which withdraws the lower selector finger and the jacks under the .220 needles are not pushed back into the cylinder on the following revolutions.

The machine is now knitting three feeds without any splicing and the positions of the thrust rods in Fig. 6 are as follows. The thrust rod 463 for the left feed stitch cam and auxiliary sinker cam is on a high portion of drum cam 508, the upper jack selector lever control thrust rod 831 70 is on the lower end of drum cam 833, the right feed clearing cam thrust rod 467 is between cams 522 and 523 on the surface of the main pattern drum, the left feed yarn finger thrust rod 460 is on the low end of drum cam 501, the jack pushout 75

cam thrust rod 464 has just ridden onto the top of drum cam 527, the right feed stitch cam thrust rod 466 has just ridden up onto drum cam 631, the left feed clearing cam thrust rod 462 is on the high portion of drum cam 506, and the right feed auxiliary sinker cam and yarn finger thrust rod 461 is on the low portion of drum cam 504.

Assuming it is desired to put fashion marks, i. e., tuck marks, in the back of the leg at the appropriate point, the manipulation of the machine to achieve this end will now be set forth. The fashion marks needles are located in the .220 needle group n' and the following .270 needle group n^2 , the needles being equidistant on either side of the dividing line between the two groups. The butts of these needles are .220 in length. The right hand stitch cam 361 at the main feed is withdrawn from operative position and the jacks are relied upon to clear the needles for the main feed. Also it should be noted that clearing cam 548, when in its operative position, is not long enough to catch the .220 butt needles and therefore clears all but the .220 butt needles. To make these fashion marks in the leg it is desired to tuck for two courses and knit off on the third course, the tucking taking place at the right feed and the main feed. To clear after the left feed, the gate clearing cam 549 is raised to the position shown in Fig. 7 by racking the main pattern drum a short distance until the thrust rod 467 under this right feed clearing cam 549 comes up from the surface of the main pattern drum onto the low drum cam 523. This last rack also causes the thrust rod 831 to ride off the high portion of its drum cam 833 onto the low step at the end thereof. This allows the upper selector control to swing partly into operative position, permitting one of the reader cams 820 to go into action. This is the so-called "fashion marks selector lever" which, acting through the pattern jacks, causes all the needles but the fashion marks needles to be raised, thereby causing tucking at two feeds on the fashion marks needles only.

When making fashion marks the needles are tucked on the right auxiliary feed and on the main feed for only one revolution of the cylinder. However, the trick wheel is racked every two revolutions, and therefore to prevent the tucking on more than one revolution the cams on the high speed gear which cause the racking of the trick wheel are adjusted in the following manner. The cam on the high speed gear which is to bring the trick wheel to position to cause tucking on the first of the two revolutions is set back slightly or delayed so that its operation does not take place until just after the tucking needles have passed the reader cam 820. On the second revolution the fashion needles tuck at the right auxiliary feed and at the main feed, i. e., they do not clear. The high speed gear carrying the cams for racking the trick wheel makes one revolution for every four revolutions of the needle cylinder and has two cams thereon to rack the trick wheel, so it is racked every two revolutions. The second cam on the high speed gear is set slightly ahead so that the trick wheel will be racked just before the tucking pattern jacks reach the selector reader fingers 820 on the third revolution. In this way the fashion marks in the leg consist of two tucks and ten cleared stitches, i. e., twelve stitches for one revolution of the high speed gear.

In the foot the tucks are made in a different manner. If fashion marks are being made in the foot, the timing of the needle cylinder with

relation to the racking of the trick wheel is such that the fashion marks jacks are pushed in for two complete revolutions. The right feed clearing cam 549 in the gate being in action at this time, clears the fashion marks needles at the right feed so that they only tuck on the main feed, making the fashion marks consist of one tuck and two plain stitches.

The next rack of the main pattern drum can be designated as the high splice rack, and at this time the pattern drum moves so as to bring the various thrust rods into the positions shown in Fig. 6. The upper selector lever control thrust rod 831 drops off the low surface at the end of cam 833 onto the surface of the main pattern drum, thus allowing all the upper selector lever reader cams to move into operative position for the varied selection in high splicing. This occurs when the center .338 needle group n^6 are opposite the reader cams 820, and thereafter all the needles that are not to knit the splicing yarn will have their jacks pushed back into the cylinder. The thrust rod 461 for the right feed yarn finger moves onto the highest portion of its drum cam 504 which moves the finger 200 into its lowermost position (see Fig. 11). The spring 214 takes up the extra motion without damaging the lever 540 which carries the sinker withdrawing cam 538. This happens when the .300 needle group n^4 , which precedes the .220 group n' , are opposite the finger. These particular needles do not take the splicing yarn—at least at the beginning of the splice—and the first needles to get the splicing yarn do so at the main throat plate. The main yarn splicing finger is dropped into action in any desired manner before the first high splice needle reaches it. The needles are raised to the splicing level at the main feed by the jacks riding up the pattern jack raising cam 741" and they are raised again at the left feed when the pattern jacks ride up the pattern jack raising cam 741". To allow the needles to take the splicing yarn at the left feed, the left feed cylinder jack idling lever 743 is moved out of operative position by the lowering of thrust rod 468, by means of a cam on the main pattern drum (not shown). This same rack moves the thrust rod 460 for the left feed yarn finger off the low portion of drum cam 501 down onto the surface of the main pattern drum. The splicing needles are now taking the path shown in solid lines in Fig. 7.

When the machine is ready to go into the making of the heel by the usual reciprocatory knitting, the main pattern drum is racked again. At the beginning of this rack the right feed stitch cam 545 drops part way out of operative position while over the leading group of .270 needles n^2 , so as to miss the .220 needle group n' and then completes its withdrawal. This is done by means of the thrust rod 466 riding down over the low end of the drum cam 631 and then to the surface of the main pattern drum. Simultaneously the right feed sinker cam and yarn finger are withdrawn by the thrust rod 461 dropping off the cam 504. The switch cam 415 moves into action to raise the instep needles, as usual. The resetting cam 747 goes out of action while over the group of .390 needles n^5 which follow the center .338 group n^6 , by the thrust rod 464 riding off the drum cam 527.

The sequence of operations affecting the left feed when going into the heel is as follows. The left feed jack idling lever 743 is moved into action by the raising of thrust rod 468 onto the cam 832 just after the first few splicing jacks have passed 75

it. Its introduction serves to drive all the remainder of the jacks back into the cylinder so that they will not be raised on the left auxiliary jack raising cam 741". The first few needles raised by their jacks at the left auxiliary feed take the splicing yarn and knit. Simultaneously with the introduction of this left feed jack idling lever 743, the resetting cam 747 is thrown out of action, thereby destroying the selection of needles by jacks. This happens while the resetting cam 747 is opposite the jacks of the following group of high butt needles, i. e., the .390 group n^5 . The left feed clearing cam 542 is withdrawn by its thrust rod 462 dropping down onto the surface 10 of the main pattern drum, while the cam is over the leading group of .300 needles, i. e., the group n^3 . In this way the needles immediately following the splicing needles which were raised by their jacks and took the splicing yarn, are left 15 at the tuck level, miss the splicing yarn and take the main yarn. These needles are drawn down by the stitch cam and thereby lay the main yarn under the sinker nebs, and then the left feed yarn guide 187 is withdrawn at the beginning of 20 the leading .270 group n^2 and the left feed stitch cam 543 is withdrawn at the same time.

When the machine has completed the heel and the preliminary regular rack in going off the heel is taking place, there is an auxiliary rack 30 which starts the return to three feed knitting for the foot. The right feed stitch cam 545 and clearing cam 548 move into action, the right yarn guide 200 and sinker withdrawing lever 540 drop into their active position, the switch cam 415 goes 35 into action to lower the idle needles, the jack resetting cam 747, the upper selector control lever 829 and the lower selector control lever drop into action, the last-mentioned driving back into the cylinder the jacks under the .220 needles so that 40 the knitting at the right feed will begin on the first needle of the last .270 group n^2 . The clearing cam 549 in the gate is raised into action (contrary to the case in the leg) and the left feed stitch cam 543 is moved into action under 45 the inactive needles, and the left feed sinker lever 483 is moved into action. Immediately thereafter the left feed jack idling lever 743 is withdrawn, the lower selector lever control is moved out of 50 action so that the .220 needle jacks are not driven back into the cylinder, and the stitch cam segment carrying cam 360 at the main feed is withdrawn over the last group of .270 needles n^2 . The left feed yarn guide 187 is lowered into position when opposite the first .270 group n^2 , but this first 55 group of .270 needles do not take the yarn, not having been cleared. The first needles to knit on the left feed are those already selected and which have knit on the right feed. The operations going into the toe are similar to those going 60 into the heel and therefore do not need to be described.

The manner of operation of the modified form in Fig. 19 will be obvious from the description of its construction. The pattern jacks 936 rise only 65 once, i. e., when going up cam 941 just prior to the right auxiliary feed. Thereafter it is the intermediate jacks 732 which raise the splicing needles at the desired points. The pattern jacks are returned to their original level by the lower 70 edge of cam 746 and cam 742. With this construction no cam for idling the pattern jacks at the left feed is shown.

What I claim is:

1. A circular knitting machine having a circle 75 of independent needles, jacks individually asso-

ciated with said needles for raising the latter to take yarns at an upper level, a normal cam path for said needles adapted to cause them to take yarns from a lower level, in combination with a yarn finger having yarn outlets at said upper and lower levels, and means adapted to raise the yarn finger to cause it to feed the lower level yarn to the needles raised by the jacks. 5

2. A circular knitting machine having a circle of independent needles, jacks individually associated with said needles for raising the latter to take yarns at an upper level, and a normal cam path for said needles adapted to take yarns from a lower level, in combination with a yarn finger having yarn outlets at said upper and lower levels, 10 means adapted to raise said finger to feed the lower level yarn to the needles raised by jacks, and means adapted to raise jacks selectively when the yarn finger is in its normal position and to raise all the jacks when the yarn finger is in its 15 raised position.

3. A circular knitting machine having a circle of independent needles, jacks individually associated with said needles for clearing and raising same to take yarns at an upper level, and a yarn finger having yarn outlets at upper and lower levels, 20 in combination with means adapted to position said yarn finger to present yarns from either the upper or lower level yarn outlets to the needles raised by the jacks, a normal cam path 25 for said needles adapted to clear same and enable them to take yarn from the lower level yarn outlet when the upper outlet yarn is presented to needles raised by jacks, said path being operative on needles not raised by the jacks, and 30 means adapted to cause the jacks to select some of the needles when the yarn finger is in its lower position, but to select all the jacks while the yarn finger is in its upper position.

4. A circular knitting machine having a circle 40 of independent needles, jacks individually associated with said needles for raising the latter to take yarns at two levels, a normal cam path for said needles adapted to take all the needles except those with short butts and to clear them 45 and present a yarn to them from the lower level, in combination with a yarn finger having yarn outlets at a plurality of levels, means adapted to position said yarn finger to present yarns at both levels or to present yarn from its lower level to 50 needles raised by jacks, and means adapted to cause said jacks to select all said needles when said yarn finger is raised, except needles with short butts.

5. A circular machine for knitting hosiery, said machine having a rotating circle of independent needles, a multiplicity of feeds and pattern jacks 55 individually associated with the needles, means adapted to select a variable number of jacks at one point on each revolution of the machine, and means causing jacks so selected to raise their needles at each of a multiplicity of feeds and to destroy the jack selection at the end of a revolution. 60

6. A circular knitting machine having a multiplicity of feeds and a circle of independent needles, pattern jacks individually associated with said needles for the purpose of raising them to take yarn fed at an upper level at each of the feeds, cam means to clear the needles at one of the feeds, means to raise the jacks at each feed so as to clear the needles at the feeds other than the clearing cam feed and present needles at each feed at an upper level to receive yarn, in combination with supplementary means prevent- 70 75

ing the jacks raising the needles at the feeds where the cam-clearing means are present.

7. A circular knitting machine having a multiplicity of feeds and a circle of independent needles, in combination with jacks individually associated with said needles for raising the latter to take yarn at an upper level, and a yarn finger at each of said feeds having yarn outlets at a plurality of levels and adapted to present yarns from its upper level to needles raised by said jacks, in combination with a cam for clearing the needles at one of the feeds and supplementary jack cam means adapted to prevent the jacks from raising the needles at the clearing cam feed.

8. A circular knitting machine having a multiplicity of feeds and a circle of independent needles, in combination with jacks individually associated with said needles for raising the latter to take yarn at an upper level, and a yarn finger at each of said feeds having yarn outlets at a plurality of levels and adapted to present yarns from its upper level to needles raised by said jacks, in combination with a cam for clearing the needles at one of the feeds, supplementary jack cam means adapted to prevent the jacks from raising the needles at the clearing cam feed, and means adapted to raise the yarn fingers at the other feeds to present yarn from the lower yarn outlet level to the needles raised by the jacks.

9. Circular knitting machine having a multiplicity of feeds and a circle of independent needles, butts of different lengths on said needles, the shortest butts being on the needles which are to tuck, jacks individually associated with said needles for the purpose of raising same to take yarns fed at an upper level, yarn feeding means at each feed adapted to present a splicing yarn at the level of the needles raised by jacks and to present a body yarn to needles not so raised, in combination with means at one or more of the feeds to adjust the yarn feeding means to present the body yarn only to the needles raised by the jacks, and means adapted to raise all the needles on the jacks at those feeds.

10. Circular knitting machine having a multiplicity of feeds and a circle of independent needles, butts of different lengths on said needles, the shortest butts being on the needles which are to tuck, jacks individually associated with said needles for the purpose of raising same to take yarns fed at an upper level, a yarn finger at each feed adapted to present a splicing yarn at the level of the needles raised by jacks and to present a body yarn to needles not so raised, in combination with means at one or more of the feeds to raise the yarn finger to present the body yarn only to the needles raised by the jacks, means adapted to raise all the needles on the jacks at those feeds, and means preventing the jacks raising the needles at one of the feeds where the yarn finger is not so raised, and cam means clearing the needles at said feed.

11. A circular knitting machine having a multiplicity of feeds, a circle of independent needles, jacks individually associated with said needles for raising same to receive yarn at an upper level, and means adapted to select jacks and make the selection effective at each of the feeds for one revolution of the machine, the raising of said needles by jacks causing the same to be cleared, in combination with cam means for clearing the needles at one or more of the feeds and supple-

mentary means adapted to prevent the jacks from raising the needles at one or more of the feeds where clearing cams are present.

12. A circular knitting machine having a multiplicity of feeds, a circle of independent needles, 5 jacks each associated with a needle for raising the latter to take yarn at an upper level, butts of different lengths on said needles, cams at a plurality of feeds adapted to act on the butts of said needles, and means adapted to insert one of 10 said cams in two stages in order to begin knitting at one of said feeds on a specific needle, in combination with means adapted to prevent the jacks from raising certain of the longer-butted needles 15 at another of the feeds on the revolution when knitting begins at that feed, in order that the cams acting on the needle butts may cause the same needle to begin the knitting on the second feed as on the first-mentioned feed.

13. A circular knitting machine having a multiplicity of feeds, a circle of independent needles, jacks each associated with a needle for raising the latter to take yarn at an upper level, butts of different lengths on said needles, cams at a plurality of feeds adapted to act on the butts of 20 said needles, and means adapted to insert one of 25 said cams in two stages in order to begin knitting at one of said feeds on a specific needle, in combination with means adapted to prevent the jacks from raising certain of the longer-butted needles 30 at another of the feeds on the revolution when knitting begins at that feed, in order that the cams acting on the needle butts may cause the same needle to begin the knitting on the second feed as on the first-mentioned feed, clearing cams 35 at said two feeds adapted to clear needles not selected by the jacks, and means adapted to cause the body yarn which was fed from the upper level at the beginning of knitting at these two feeds to be fed to the needles not selected 40 by the jacks and the splicing yarn to be fed to the needles which are selected by the jacks.

14. A circular knitting machine having a rotating circle of independent needles, a multiplicity of feeds, jacks individually associated with 45 the needles, means at one point on the cam circle adapted to select jacks for varied splicing, means causing jacks so selected to divide the needles from the single selection at a multiplicity of feeds and means to provide a different jack selection after passage of the needles through a multiplicity of feeds.

15. A circular knitting machine for knitting stepped splice at a multiplicity of feeds, comprising a rotating circle of independent needles, 55 a multiplicity of feeds, jacks individually associated with the needles, means at one point on the cam circle adapted to select jacks for stepped splicing, means causing jacks so selected to divide the needles from the single selection at a multiplicity of feeds and means to provide a different jack selection after passage of the needles 60 through a multiplicity of feeds.

16. A circular machine for knitting hosiery, said machine having a multiplicity of feeds, a 65 rotating circle of independent needles and pattern jacks individually associated with the needles for the purpose of raising them, means at one point on the cam circle adapted to select jacks for tucking, and means causing jacks so selected 70 to divide the needles from the single selection at a multiplicity of feeds and to change the jack selection at the end of a multiplicity of feeds.
